UNITED STATES PATENT OFFICE.

ALFRED C. MURR AND FRANK L. CURRAN, OF CHICAGO, ILLINOIS.

WASHING DEVICE.

Application filed November 24, 1924. Serial No. 751,772.

Our invention relates to washing devices and has for a primary object the provision of simple and inexpensive apparatus, by means of which the ordinary wash boiler may be quickly and conveniently converted into an automatic washing device, though it will be apparent from the description that said apparatus is not necessarily confined to this use, but may be incorporated in washing or sterilizing devices of many different general types.

An important feature of the invention is the provision of a washing device adapted to be readily assembled and adjusted to different conditions of use and to efficiently operate in accordance with the principle of thermal siphonic action and in the manner of a percolator, to thoroughly sterilize and cleanse clothes, or other articles placed in the device to be washed.

Numerous other objects and advantages of the invention will be apparent as it is better understood from the following description, which, taken in connection with the accompanying drawings, discloses a preferred embodiment thereof.

Referring to the drawings,

Figure 1 is an elevational view, partially broken away and shown in section, of a washing machine in which the principles of our invention are embodied; and

Fig. 2 is a plan view of the interior parts, being taken through the boiler or receptacle substantially upon the section line 2—2 in Fig. 1.

Upon the drawings embodying the best manner in which we have contemplated applying the principles of our invention, the reference character 11 indicates a receptacle which may be in the form of an ordinary wash boiler and is adapted to be closed by means of a lid 12 provided with a handle 13. A peripheral flange 14 extends downwardly from the bottom 15 of said boiler and is adapted to rest upon a grate or grid 16, disposed above burners 17 of a gas stove or the like, it being understood that the device is adaptable for use with practically any kind of heating facilities which may be available.

For the purpose of creating an action of the water which will efficiently perform the functions of the device, we provide one or more (preferably two) bell-shaped members 18 adapted to be positioned within the receptacle 11 and over the spots in the bottom 15 which are immediately above the burners

17 and are thus subjected to greatest heat. We also provide hollow uprights 19, which extend through apertures 20 in the top of said members 18 and are held in place by means of clamping nuts 21 and 22 threaded onto the lower ends of said uprights and disposed respectively below and above the top walls 23 of said members 18. The tubular uprights 19 are provided with caps 25 at the top thereof and are perforated as indicated at 26 throughout a considerable portion of their length from the top downwardly.

The members 18 are provided with a desired number of recesses 27 at the edge thereof, which recesses provide inlet passages for the water, which is subjected to relatively high temperature within said members 18 and is thus forced upwardly through the tubes 19 and projected violently through the perforations 26 and about the interior of the boiler. The form of the members 18 serves to direct the ascending water into the tubes 19 and the relatively small openings 27 provide an intake for the water from the bottom of the boiler so that a continuous circulation is maintained, the action being substantially that of a percolator. The water within the bells 18, upon being rapidly raised to temperature considerably higher than that of the remaining water in the boiler, is forced upwardly, in accordance with natural law, and the incoming water is heated so rapidly that the circulation is continuous and automatic.

Tests have shown that a circulation of approximately 500 complete revolutions per minute may be attained with the device and that the water is projected with such force as to cause it to permeate the closest woven materials.

In order that the bells 18 may be positioned over the hot spots on the bottom of the boiler under varying conditions, they are freely movable and we provide base plates 28, which are provided with apertures 29 to permit the water to drain therethrough, the outer ends of said plates being provided with projecting portions 31 formed to fit over the upper portions of the bell-shaped members 18 and to conform to the shape thereof. Said base plates 28 are provided with depending side flanges 32, adapted to be interengaged, and it will be obvious that the members 18 may be positioned at varying distances apart, in accordance with the arrangement of the burners and the size of the receptacle 11. Said plates preferably overlap a considerable

distance, so that a substantial range of adjustment is provided and a continuous supporting surface for the clothes, or other articles, will be maintained under all conditions.

5 The manner in which the parts are clamped together greatly facilitates the assembly and demounting thereof, it being possible to position and remove the nuts 21 and 22 and to arrange the parts 18 and 28 very quickly and 10 easily, and the apparatus being adapted to be packed, when demounted, in relatively small space for storage and shipment. The portability of the apparatus is a highly important feature, from the standpoint of price 15 at which it may be sold and convenience in use.

It is thought that the invention and many of its attendant advantages will be understood from the foregoing description, and it 20 will be apparent that various changes may be made in the form, construction and arrangement of the parts without departing from the spirit and scope of the invention, or sacrificing all of its material advantages, the 25 form hereinbefore described being merely a preferred embodiment thereof.

We claim:

1. A washing device adapted to be inserted 30 in a wash boiler, comprising, two hollow members, each having an open mouth adapted freely to rest on the bottom of the tub, the upper portions of said members being perforated, a tube having a threaded end inserted in the perforation of each member, 35 two sheet metal members, each having an aperture adapted to register with the mouth

of the tubular member and nuts threading on said tube and maintaining the tube, the sheet metal members and the tubular members in assembled relation, said sheet metal members being arranged in overlapping relation between said hollow members to provide a clothes support. 40

2. A washing device, comprising, a bell-shaped member, a second bell-shaped member, 45 each of said bell-shaped members having recesses at their mouths to provide water inlets, and each of said bell-shaped members being perforated at points opposite the open mouths, tubes projecting through said perforations, sheet metal plates each having an arcuate projection at one end having a perforation to register with the perforation in one of said bell-shaped members with the tube passing through said perforations and 55 threaded nuts on said tubular member above and below said perforations, holding said bell-shaped member, plate and tube in assembled position, the upper end of each tube being perforated to provide water discharge, 60 each of said plates at one side of said arcuate portion being relatively long and wide, and perforated, and each of said plates having curved edges, one of said plates being wider than the other, whereby the curved edges of 65 one of said plates slide in the curved edges of the other of said plates, whereby to permit the adjustment of said bell-shaped members toward and from each other while maintaining the sliding engagement of said plates. 70
